[57] CLAIM

The ornamental design for an automobile top attachment, as shown and described.

DESCRIPTION

FIG. 1 is a side elevational view of an automobile top attachment showing our new design, the broken lines being for illustrative purposes only;

FIG. 2 is a perspective view thereof;

FIG. 3 is a top plan view thereof;

FIG. 4 is a side elevational view thereof, the opposite side being a mirror image of the side shown herein;

FIG. 5 is a bottom plan view thereof;

FIG. 6 is a front elevational view thereof; and

FIG. 7 is a rear elevational view thereof.

FIG. 2**FIG. 1**
